CLAIM

The ornamental design for a sideboard, as shown and described.

DESCRIPTION

FIG. 1 is a perspective view of a sideboard showing my new design;

FIG. 2 is a front elevational view thereof;

FIG. 3 is a right side elevation thereof, the left side elevation being a mirror image;

FIG. 4 is a top plan view thereof; and,

FIG. 5 is a sectional view taken along line 5—5 of FIG. 2. The rear of the sideboard is flat and unornamented.
